HINGE CONSTRUCTION FOR SWINGING
OVERHEAD DOOR
Henry P. Lipking, 4987 E. Tulare St.,
Fresno, Calif. 93702
Filed Feb. 21, 1966, Ser. No. 529,031
7 Claims. (Cl. 16—163)

ABSTRACT OF THE DISCLOSURE

A plate-like mounting bracket for a pair of pivoted support arm means of an overhead door and including adjustable abutment stop means for limiting swinging movement of the support arm means and also anchor means for attachment of one end of an elongated counterbalance spring to the mounting bracket.

This invention relates to a novel and useful hinge construction for a swinging overhead door and more specifically to various improvements which have been made to the similar inventions disclosed in my prior U.S. Patent No. 2,751,624, dated June 26, 1956, for Spring Anchor Unit for Overhead Swinging Doors and my prior U.S. Patent No. 3,254,364, dated June 7, 1966, for Jamb Type Hinge for Overhead Doors.

The hinge construction of the instant invention includes an improved doorstop for limiting swinging movement of the associated door to the open position as well as an improved doorstop for limiting swinging movement of the associated door to the closed position. Further, the improved hinge construction of the instant invention additionally includes an improved pivotable spring anchor for securing one end of the associated counter-balance spring to the corresponding door.

Some similar types of overhead doors utilize an elongated bumper constructed of either rubber or felt composition nailed to the undersurface of the header defining the upper extremity of the corresponding door opening as a limit stop for swinging movement of the garage door to the open position. This type of bumper engages the overhead door along a generally horizontally disposed line adjacent the bottom edge of the door when the door is in a closed position and has a tendency to discolor the paint on the exterior surface of the door or otherwise mar the outward appearance of the door such as by chipping the paint therefrom along the aforementioned line. The improved doorstop of the instant invention for limiting swinging movement of the associated overhead door to its open position has as its main object to provide a means whereby upward swinging movement of the overhead door to the open position may be limited by means of an abutment stop carried by the support bracket of the door and engageable by one of the support arms of the door.

Further, present methods of limiting downward swinging movement of an overhead door to the closed position involve the utilization of metal clips disposed near the lower portions of the vertical side members of the door-jamb and extending outward to contact the door as it moves to its final closed position. These protruding clips are disposed close to the ground and usually project in a manner so as to be engageable by the lower portions of the legs of a person walking through the door opening adjacent one vertical side member of the jamb defining the opening. It is accordingly a further important object of this invention to provide a doorstop for an overhead door including means by which an abutment is provided carried by the mounting bracket for the door and engageable by one of the support arms of the door for limiting downward swinging movement of the door to its closed position.

2

Still another object of this invention, in accordance with the preceding objects, is to provide doorstops for an overhead swinging door supported from the mounting brackets for the door in a manner such that the limit positions of movement of the associated overhead swinging door to the open and closed positions may be readily adjusted.

A still further object of this invention is to provide a spring anchor arm for one end of the counterbalance spring of the overhead door assembly which is adapted to be pivotally secured to the door in a manner such that the anchor arm, the expansion-type counterbalance spring and the anchor for the end of the spring remote from the anchor arm will be maintained in perfect alignment during swinging movement of the door from the open position to the closed position.

A final object of this invention to be specifically enumerated herein is to provide a hinge construction for swinging overhead doors which will conform to conventional forms of manufacture, be of simple construction and easy to install so as to provide a device that will be economically feasible, long lasting and relatively trouble free in installation.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

FIGURE 1 is a fragmentary vertical sectional view taken through a door opening and illustrating the hinge construction of the instant invention supported from the door jamb and operably swingably supporting the associated door for movement between closed and open positions, the overhead swinging door being illustrated in the closed position;

FIGURE 2 is a fragmentary elevational view of the assemblage illustrated in FIGURE 1 as seen from the left side thereof;

FIGURE 3 is a fragmentary vertical sectional view similar to that of FIGURE 1 but illustrating the overhead door in its full open position;

FIGURE 4 is an enlarged fragmentary horizontal sectional view taken substantially upon the plane indicated by the section line 4—4 of FIGURE 3;

FIGURE 5 is a fragmentary vertical sectional view taken substantially on a plane indicated by the section line 5—5 of FIGURE 3 and on somewhat of an enlarged scale;

FIGURE 6 is a perspective view of a support bracket or anchor plate portion of the hinge construction; and

FIGURE 7 is a perspective view of one of the abutment members of the hinge construction utilized to limit swinging movement of the overhead door to the open position.

Referring now more specifically to the drawings, the numeral 10 generally designates a door jamb construction including an upright 12 and a horizontal header 14. Of course, the door jamb 10 includes a second upright 12 and defines a door opening between the uprights 12, the ground 16 and the header 14.

An overhead swinging door 18 is provided and includes a pair of upstanding opposite side marginal edge portions 20 snugly received between the uprights 12. The hinge construction of the instant invention is generally referred to by the reference numeral 22 and is of course utilized in pairs with one hinge construction 22 being supported from each upright 12 and operatively connected to the corresponding upstanding marginal edge portion 20 of the door 18.

Each hinge construction 22 includes a mounting bracket 24 including a first flange portion 26 secured to the corresponding upright 12 in any convenient manner such as by fasteners 28 and a second plate-like flange por-

tion 30 disposed at right angles relative to the flange portion 26. The flange portion 30 is disposed in an upstanding plane normal to the plane of the door opening and includes a rear marginal edge portion 32 facing away from the corresponding upright 12.

A master support arm 34 has one end thereof pivotally supported from the flange portion 30 by means of a pivot pin 36 and the other end of the support arm 34 is pivotally secured to an anchor bracket 38 secured to the corresponding upstanding marginal edge portion 20 of the door 18. The support arm 34 is pivotally secured to the anchor bracket 38 by means of a fastener 40 and the anchor bracket 38 is secured to the door 18 by means of fasteners 42. A second support arm 44 is provided and has one end pivotally supported from the flange portion 30 by means of a suitable pivot fastener 46 and the other end of the support arm 44 is pivotally supported to an adjustment bracket 48 by means of a suitable pivot fastener 50. The adjustment bracket 48 is secured to the anchor bracket 38 by means of suitable fasteners 52 secured through the anchor bracket 38 and slots 54 formed in the adjustment bracket 48 whereby the adjustment bracket 48 may be adjusted longitudinally of the anchor bracket 38 so as to adjustably incline the door 18 when it is in its closed position. This adjustability of the adjustment bracket 48 accordingly provides a means whereby the door 18 may be adjusted so as to be substantially vertically disposed when in the closed position.

The flange portion 30 is provided with a horizontal slot 56 in an area disposed approximately midway between the vertically spaced pivot pins or fasteners 36 and 46 and a shoulder bolt 58 is secured through the slot 56 by means of a suitable fastener 60, the shoulder bolt 58 having a resilient sleeve covering 62 disposed thereon which is engageable by the main support arm 34 when the door 18 is in the closed position, see FIGURE 1.

An anchor bracket generally referred to by the reference numeral 66 is provided and is generally U-shaped in configuration including a first plate-like leg 68, a second plate-like leg 70, and a plate-like bight portion 72 interconnecting corresponding ends of the generally parallel legs 68 and 70. The anchor bracket 66 is constructed of stiff but resilient material and the leg 68 thereof has a vertically disposed slot 74 formed therein. The anchor bracket 66 is secured to the flange portion 30 by means of a fastener 76 secured through a horizontal slot 78 formed in the flange portion 30 and the vertical slot 74 formed in the leg 68. The leg 68 has its end adjacent the bight portion 72 disposed immediately adjacent the rear marginal edge portion 32 of the flange portion 30 and the bight portion 72 passes immediately behind the rear marginal edge portion 32 and projects outwardly of the side of the flange portion 30 on which the arms 34 and 44 are pivotally supported. The leg 70 projects forwardly from the bight portion 72 toward the door opening defined by the jamb 10 and is apertured as at 80 on its free end. An elongated pivot fastener 82 is secured through the aperture 80 and has one hooked end of an expansion spring 84 engaged therewith. The other end of the expansion spring 84 is engaged with an eyebolt 86 threadedly secured through an angulated flange portion 88 of a generally L-shaped anchor arm 90 whose end remote from the flange portion 88 is pivotally supported from the anchor bracket 38 by means of a pivot fastener 92.

Also pivotally supported from the pivot pin 82 is one leg portion 94 of an L-shaped abutment bracket 96 including a second leg portion 98 covered with a resilient sleeve 100 and disposed for engagement by the main support arm 34 when the door 18 is in its fully open position, see FIGURE 3.

The leg portion 94 has an elongated slot 102 formed therein through which the pivot pin or fastener 82 extends.

It is believed readily apparent that the abutment bracket 96 may be readily adjusted to variably limit swinging

movement of the arm 34 during movement of the door 18 to the open position by vertically adjusting the anchor bracket 66. Further, the abutment defined by the shoulder bolt 58 may also be readily adjusted so as to vary the limit position of swinging movement of the support arm 34 during movement of the door 18 to the closed position by horizontally adjusting the shoulder bolt 58.

The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to, falling within the scope of the invention as claimed.

What is claimed as new is as follows:

1. In combination, a doorjamb defining an upstanding door opening, a mounting unit for an upstanding door for said opening swingable to an overhead open position, said unit comprising a mounting plate secured to said jamb appreciably below the upper extremity of said opening and including at least one upstanding portion spaced laterally at one side of and disposed generally normal to the plane of said opening, arm means including a pair of door attaching arms pivotally secured at one pair of corresponding ends to one side of said upstanding portion for rotation about vertically spaced horizontal axes generally paralleling said plane, means on the other pair of ends of said arms adapted to pivotally secure said other ends to said door in vertically spaced relation, first and second abutment means disposed to said one side of and carried by said one portion and engageable by said arm means to limit swinging movement thereof in opposite directions, said arms being disposed in generally upright positions when said arm means is engaged with said first and second abutment means, said abutment means being supported from said upstanding portion for adjustment laterally of said plane, abutment means including a generally L-shaped plate having a first leg portion pivotally supported from and generally paralleling said upstanding portion and a second leg portion extending laterally outwardly of the free end portion of said first leg portion with which one of said arms is engageable.

2. In combination, a doorjamb defining an upstanding door opening, a mounting unit for an upstanding door for said opening swingable to an overhead open position, said unit comprising a mounting plate secured to said jamb appreciably below the upper extremity of said opening and including at least one upstanding portion spaced laterally at one side of and disposed generally normal to the plane of said opening, arm means including a pair of door attaching arms pivotally secured at one pair of corresponding ends to one side of said upstanding portion for rotation about vertically spaced horizontal axes generally paralleling said plane, means on the other pair of ends of said arms adapted to pivotally secure said other ends to said door in vertically spaced relation, first and second abutment means disposed to said one side of and carried by said one portion and engageable by said arm means to limit swinging movement thereof in opposite directions, said arms being disposed in generally upright positions when said arm means is engaged with said first and second abutment means, said abutment means being supported from said upstanding portion for adjustment laterally of said plane, said unit including a generally U-shaped plate including one leg secured to the other side of said upstanding portion, a bight portion extending outwardly from one side of said one leg and behind the marginal portion of said upstanding portion remote from said plane, and a second leg extending laterally outwardly of one side of the end of said bight portion remote from said one leg toward said plane, and an expansion spring including a first end anchored to the free end portion of said second leg and a second end adapted to be anchored

70 75 to a lower portion of said door.

3. The combination of claim 2 wherein said U-shaped plate is supported from said upstanding portion for vertical adjustment relative thereto.

4. The combination of claim 1 wherein said one of said attaching arms is engageable with said first abutment means in one limit position of said arm means and said second abutment means when said arm means is swung to the other limit position of swinging movement thereof.

5. The combination of claim 4 wherein the other of said arms includes a mounting bracket pivotally secured to the end thereof remote from said mounting plate and adapted for securement to said door in vertically adjusted positions.

6. The combination of claim 2 wherein said second end of said expansion spring includes means adapted for se-

curement to said door and to adjust the tension of said spring.

7. The combination of claim 1 wherein said first and second abutment means are disposed above and below the end of said one attaching arm secured to said plate and said second abutment means being disposed above the end of the other attaching arm secured to said plate.
